(57) **CLAIM**

The ornamental design for a flash memory drive, as shown and described.

DESCRIPTION

FIG. 1 is a side, top, perspective view of the flash memory drive including the housing and end cap with side openings and a surface label area thereof shown in phantom; FIG. 2 is a top view thereof, the bottom view being a mirror image thereof;

FIG. 3 is a rear view thereof;

FIG. 4 is a left side view thereof;

FIG. 5 is a front view thereof; and,

FIG. 6 is a side, top, perspective view of an exploded view of the flash memory drive device with an end cap removed and the exposed clip and connector portions shown thereof in phantom.

1 Claim, 1 Drawing Sheet

FIG. 2

FIG. 3

FIG. 6
